UNITED STATES PATENT OFFICE.

SOREN G. SORENSEN, OF VALLEY JUNCTION, WISCONSIN.

DANGER-SIGNAL FOR RAILROADS.

1,323,418.

Specification of Letters Patent.

Patented Dec. 2, 1919.

Application filed August 7, 1916. Serial No. 113,566.

To all whom it may concern:

Be it known that I, SOREN G. SORENSEN, a citizen of the United States, residing at Valley Junction, in the county of Monroe, 5 State of Wisconsin, have invented certain new and useful Improvements in Danger-Signals for Railroads; and I do hereby declare the following to be a full, clear and exact description of the invention, such as 10 will enable others skilled in the art to which it appertains to make and use the same.

The present invention relates to danger signals for railroads, and has for its object to construct a device of this character 15 which will indicate that a wash-out in the roadbed has occurred.

A further object is to provide a device of this character so constructed that the signals indicating a wash-out can be discerned either in the day time or at night.

A still further object of the invention is to provide a device of this kind having means for resetting the parts after the same has been operated.

Still another object of the invention is to provide means whereby a station agent will be notified that a wash-out has occurred so as to warn an oncoming train, or send a crew to the place of danger for 30 making repairs.

With these and other objects in view, this invention resides in the novel features of construction, formation, combination and arrangement of parts to be hereinafter more 35 fully described, claimed and illustrated in the accompanying drawing, in which:—

Figure 1 is a front elevation of the device.

Fig. 2 is a vertical central sectional view 40 therethrough.

Fig. 3 is a sectional view on line 3—3 of Fig. 2.

Fig. 4 is a sectional view of the upper portion of the device, corresponding to Fig. 2, 45 but with the parts enlarged and in position when the signals are operative.

Fig. 5 is a side elevation.

Fig. 6 is a top plan view.

Referring to the drawing, 1 indicates a 50 post, which may be of any formation found suitable, and in one side of which is rotatably mounted a shaft 2 having a lug or a ratchet tooth 3 projecting from its periphery, the purpose of which will appear 55 later. Fixed to the shaft is a signal arm or semaphore 5. The arm 5 is fixed to the

shaft 2 so that one arm is longer than the other, and when the lug 3 is engaged with the pawl 6 the arm will be held in a vertical position, said pawl being pivotally 60 connected to the post 1. The arm 5 is thus mounted to one side of its longitudinal axis to swing vertically when released, one arm thus being longer than the other.

A plate 7 is pivotally connected near the 65 upper end of the post and has a chain 7' connected to its under surface, and to this chain is connected the upper end of the rod 8, the lower end of which has a turn-buckle 9 to which a rod 10 is connected, said rod 70 being flexibly connected to the weight 11.

Connecting the pawl 6 and rod 8, at a point above the shaft 2 is a chain 12, which chain passes over the pulley 13 supported by the post, so that a downward movement 75 of the rod 8 will raise said pawl to release it from the lug 3 to permit the arm 5 to turn to an operative position.

The post carries a box 14 in which are mounted the batteries 15, and pivotally 80 connected to the post 1 adjacent the box 14 is a contact plate 16 connected to the rod 8 by the chain 17. Circuit wires 18 lead from the batteries to the depot, so that when the plate 16 is moved downwardly 85 into engagement with the contact 19 the circuit will be closed so as to notify the station agent that a wash-out has occurred.

A casing 20 is supported by the post and has mounted therein an incandescent light 90 21, connected with the batteries by the circuit wires 22. Mounted on the casing 20 is a contact rod 23 which is encircled by the coil spring 24, serving to absorb the jar when the weight 11 drops and the plate 95 7 engages said spring. After the plate 7 has been moved downwardly by the weight 11 the latch 25 will move inwardly under the action of the coil spring 26 so as to engage the plate 7 thereby holding the 100 same in contact with the rod 23 so that the light will glow until the circuit is broken.

This is caused by the engagement of the plate 7 with the contact rod 23 so as to close the circuit through the batteries and lamp 105 21. As long as the weight 11 remains attached to the rod 8, the plate 7 will be held down, and the purpose of providing the catch 25 is to hold the circuit closers or switches in contact and thus to hold the 110 circuits closed in case the weight should break loose from the chain and rod 8, in

dropping from the bank or the like which previously supported it, for instance, adjacent to a stream, due to a wash-out, or be carried off by the stream.

5 Pivotedly connected to the post 1 near its lower end is a lever 27 which has connected thereto a chain 28 engaged around the pulley 29, and connected with the chain is a rod 30 having a chain 31 connected to its 10 upper end and also engaged over a pulley 32, said chain being connected to the latch 25 so that when the rod 30 is moved downwardly upon upward movement of the lever 27 the latch will disengage the plate 7 so 15 that the spring 24 will force the same upward thus breaking the circuit to extinguish the light providing the weight 11 has broken loose.

A chain 33 has one end connected to the 20 rod 30 and the other end to the lug shaft 2 so that the shaft 2 can be rotated to its normal position when the rod 30 is moved downwardly so that the lug 3 will again engage the pawl 6, thus holding the arm 5 25 in a vertical or inoperative position. It is of course, to be understood, that in the illustration the arm 5 swings to the right when moving to a horizontal position and vice versa, the long arm being held upward when 30 the shaft 2 is held by the pawl 6. It is also to be understood that when the latch 25 is released, the spring 24 is sufficiently strong to raise the plate 7 and the rod 8 providing the weight 11 has broken loose, but otherwise, the weight 11 must be lifted and allowed to rest upon a support, as when set 35 for operation, to allow the parts of the device to return to initial position after the operation of the lever 27 to release the catch 25 and return the arm 5 to a vertical position by turning the shaft 2 through the medium of the chain 33, which chain serves to limit the turning of the arm 5 to a horizontal position by its overbalancing weight, 40 when the pawl 6 is released, the chain 33 pulling taut with the rod 30 in carrying out this function. It is of course understood that the lever 27 is in its downward position when this operation is taking place, 45 the upward swinging of the lever 27 causing the turning of the shaft 2 to reset the arm 5 and to release the plate 7, as heretofore specified.

The post 1 is arranged in a place where 50 a wash-out is most likely to occur, and the weight can be either engaged with the ties or on the ground adjacent the track so that when the weight moves downwardly it will pull upon the rod 8, and at which time the 55 chain 12 will disengage the pawl 6 from the stop or lug 3 so that the arm 5 will swing from a vertical to a horizontal position, and simultaneously with the swinging of the arm the plates 7 and 16 will be actuated to 60 close the respective circuits connected there-

by. Of course it will be obvious that when the lever 27 is moved upwardly and when it is desired to reset the parts the rod 30 will be pulled downwardly thus swinging the latch 25 outwardly so that the plate 7 70 can swing upwardly, and at the same time the shaft 2 will be rotated through the medium of the chain 33 to return the arm 5 to its vertical position, where it is held by the pawl 6 engaging the lug 3 as before, the 75 flash or light 21 and the signal at the station or depot being rendered inoperative by the automatic disengagement of the spring contacts 7 and 24, and 16 and 19.

What is claimed is:—

1. A danger signal for railroads and the like, comprising a post, a plate pivoted in the post, a flexible connection suspended from the plate, a weight at the lower end of the connection, a series of signals adapted to be actuated upon downward movement of the plate under the action of the weight when the latter is released from a supporting position, means to hold said plate downwardly disposed and means to lift the plate 80 upon release of the first named means, should the weight be detached.

2. A danger signal for railroads of the class described, comprising a hollow post, a shaft rotatably mounted thereon, a signal 95 arm fixed to the shaft exteriorly of the post, a rod movable vertically within the post and having a weight connected with its lower end, means for holding said shaft in one position of rotation, means for rotating the 100 shaft when the rod is shifted, a swinging plate connected to the rod, means to hold said plate in a downward position, means for releasing said holding means and resetting the same, means for causing upward 105 movement of the plate together with the rod and additional signaling means operative upon the downward movement of the rod, simultaneously with the operation of the signal arm and inoperative upon the raising 110 of the plate.

3. A signaling device of the class described, comprising a post, a shaft rotatably mounted therein, in a horizontal position, a normally vertical signal arm fixed to the 115 shaft, a rod movable vertically in the post and having a weight connected with its lower end, said shaft having a lug thereon, a pawl within the post and having engagement with the lug to hold the arm in a vertical position, said pawl also having connection with the rod for releasing the pawl upon downward movement of the rod, a second rod also movable vertically within said post and having connection with the shaft 125 for turning the latter to move the arm to a vertical position and means to hold the rod in a raised position.

4. A signaling device of the class described, comprising a post, a shaft rotatably 130

mounted therein in a horizontal position, a normally vertical signal arm fixed to the shaft, a rod movable vertically in the post and having a weight connected with its lower end, said shaft having a lug thereon, a pawl within the post and having engagement with the lug to hold the arm in a vertical position, said pawl also having connection with the rod for releasing the pawl upon downward movement of the rod, a second rod also movable vertically within said post and having connection with the shaft for turning the latter to move the arm to a vertical position, a movable support within the post to which said first named rod is connected, means normally holding said support in a raised position independently of the weight, means for releasing said last mentioned means through the medium of the second named rod when moving the arm to a vertical position to be held by the engagement of the pawl with the lug of the shaft, and local and distant signal devices having connection with the first named rod and including electrical circuits closed upon the downward movement of the rod simultaneously with the actuation of the arm and automatically releasing upon the raising of the rod together with its supports under the action of the raising means therefor, or upon releasing the rod first named of the load of its weight.

In testimony whereof, I affix my signature, in the presence of two witnesses.

SOREN G. SORENSEN.
